PAPER CLIP

Hugh P. Botts, New York, N. Y., assignor of one-half to Lawrence G. Botts, New York, N. Y.

Application December 16, 1944, Serial No. 568,477

3 Claims. (Cl. 24—81)

1

This invention relates to what is commonly referred to as paper clips. More particularly, the invention deals with devices of this kind shaped to form mounting or supporting loops whereby a number of sheets of paper may be supported by the clip from a supporting member or whereby a plurality of groups of sheets or the clips of each group may be joined to maintain the plurality of groups in associated relationship to each other, particularly when dealing with a common subject. Still more particularly, the invention deals with clip devices of the kind described which are adapted for assemblage on a mounting or binder as individual clips or as united clips. The novel features of the invention will be best understood from the following description when taken together with the accompanying drawing, in which certain embodiments of the invention are disclosed, and in which the separate parts are designated by suitable reference characters in each of the views; and in which:

Fig. 1 is a perspective view of one paper clip made according to my invention.

Fig. 2 is a view similar to Fig. 1, showing a number of clips arranged upon an elongated uniting member or loop.

Fig. 3 is a view similar to Fig. 2 showing the clips arranged upon a spring ring.

Fig. 4 is an extended perspective view showing a plurality of clips united through the medium of connecting links.

Fig. 5 is an enlarged perspective view showing the supporting or mounting end portion of a paper clip made according to my invention and showing a modification.

Fig. 6 is a perspective view of a number of clips coupled together showing another form of construction.

Fig. 7 is a view similar to Fig. 1 showing an elongated open type of mounting loop.

Fig. 8 is a view illustrating a use or mounting of clips as shown in Fig. 7.

Fig. 9 shows another adaptation and use of clips substantially similar to those shown in Figs. 7 and 8; and

Fig. 10 is a perspective view showing the manner of uniting clips substantially as taught in Figs. 6 and 9 of the drawing.

In paper clips, particularly of the type and kind formed from bent wire, comprising two elongated loops, and extensively used for uniting several sheets of paper, such devices have been utilized solely for this purpose and have been constructed to adapt them for this use. It is

2

the purpose of my invention to provide paper clips of the kind under consideration with mounting loop ends whereby the clip may be utilized to suspend or otherwise support clamped sheets, or to mount a plurality of groups of sheets on a common mounting or binder. Still further to secure a predetermined number of clips together so as to provide a unit assemblage by which several groups of papers may be maintained in united or coupled relationship to each other.

Very often, it is essential to maintain a large number of papers all dealing with a common subject in coupled relationship to each other. With the present type of clip constructions, it has been undesirable and impossible to retain a large number of sheets in proper assembled relationship, whereas the clips work very satisfactorily on a limited number of sheets. By my improved construction and by providing in any given unit the required number of clips for maintaining an assemblage of a large number of documents or sheets, these documents or sheets can be successfully and securely retained in position by subdividing the sheets or documents into small groups, each united by a single clip of the unit. It will also be apparent that assemblages of the clips may be so made that gripped sheets or documents may be moved one relatively to the other without disturbing the relationship of the other sheets in substantially the manner of turning the pages of a book, and yet without being restricted to binding, as would prevail in a book, in that each group of sheets may be freely moved with respect to other groups of sheets without displacing the sheets in each group from the supporting clip.

In some instances, a number of individually clipped groups of papers may be simply united or bound together by a string, wire or other uniting medium which will be passed through the supporting or binding loop of all of the clips employed. In still other instances, and to insure united relationship between the clips, the clips may be joined one with the other through the medium of the mounting loops thereon.

In Fig. 1 of the drawing is shown a single paper clip illustrating one adaptation of my invention. This clip is generally identified by the reference character 15, and is of more or less conventional type, insofar as being provided with a long loop 16 and a shorter loop 17 between which papers are adapted to be clipped or clasped by a tensional engagement between the substantially parallel side walls of the two loops 16 and 17 as in other devices of this kind. Here again it is to be borne

in mind that the so called shorter loop 17 is of less diameter and fits within or upon the larger diameter loop 16, again as in devices of the kind under consideration.

In conventional devices, one side 18 of the loop 16 has been integrally united with one side 19 of the smaller loop 17 in a looped end portion. This end portion 20 of my improved clip has been preferably extended or made longer than the conventional loop and is shaped, as shown in Fig. 1, to form a substantially closed small mounting ring or loop 21, the closure being accomplished by contraction of the wire, as seen at 22, and this contraction may be considered a neck portion. In this contraction is also formed a twist which disposes the loop or ring 21 substantially at right angles to the loops 16 and 17. In other words, the loops 16 and 17 are flat and parallel one with respect to the other for the purpose for receiving the sheets to be engaged thereby, whereas the loop 21 would have its opening 23 at right angles to the openings of the loops or with the loop 21 perpendicular to the sheet. With clips of this type and kind, the papers or sheets to be engaged by the clip will extend up to the neck portion or to the point indicated by the dot and dash line 24 of Fig. 1, thus leaving the loop 21 disposed beyond the edge of the sheet. It will thus be seen that any type of mounting can then be passed through the opening 23 of the loop 21 to suspend or hang the clip with the sheets thereon from any suitable support or to unite several clips, with independent sheets supported in each clip, one with the other.

In Fig. 2 of the drawing is shown one method of uniting a number of clips 15. For example, on an elongated mounting ring holder or member 25. The member 25 is in the form of an open elongated wire pin having a shank 26 adapted to be passed through the loops 21 of the clips 15 when in open position, and after the clips have been assembled, the shank 26 is moved into engagement with a hook end 27, forming the closed ring like member 25.

In Fig. 3 of the drawing, I have shown three of the clips 15 having their looped ends 21 mounted upon a ring like binder or member 28, somewhat similar to a key ring, the member 28 having overlapping spring end portions 29 and 30, over either of which the loops 21 may be threaded for uniting the clips on the member 28.

In Fig. 4 of the drawing a number of the devices or clips 15 have their looped ends 21 joined by coupling links 31, each link having curled end portions 32 which extend around the wall portions of the loops 21, one end of each link being united with a loop 21. In coupling several clips together, adjacent links will have adjacent ends united with a loop 21 of a single clip, as is clearly illustrated in Fig. 4 of the drawing. Clips of the general type and kind shown in Figs. 1 to 4 inclusive and in fact, of the type and kind later described in connection with Figs. 5 to 9 inclusive may have their looped ends united one with the other in directly coupling the clips together without the use of a separate coupling, mounting or binding member, such as the members 25 and 28, and the links or members 31.

In Fig. 6 of the drawing, for illustrative purposes, I have shown four of the clips 15 having their mounting loops 21 united with each other. The loop of the clip 33 extends through the loop of the adjacent clip 34 and the loop of the clip 35 also extends through the loop of the clip 34 and through the loop of the clip 36. In this con-

nection, it will be understood that the loops 21 will be made sufficiently large in diameter to permit the assemblage described. It must be borne in mind, that the particular shape or contour of the loops 21 may be made to suit intended uses, and while for most purposes it would be practical and desirable to keep these loops within the size of the larger loop 16, of the clip itself, this is not essential. Furthermore, the extent of closure of the loops may be varied as well as the extent of opening of the loops. Still further, the particular angular arrangement of the loops may be modified to suit different conditions, and in some instances, these loops may be disposed substantially in the same plane as the loops of the clip. In other words, in Fig. 5 of the drawing is shown a modification wherein the mounting or suspending loop 37 of a clip 38 is arranged substantially in the same plane as the loops of the clip, or in other words, the opening 39 will be parallel to sheets supported in the clip rather than at right angles thereto as with the loops 21. The clip 38 is otherwise of the same construction as the clip 15, and for this reason, the remainder of the clip is not shown in Fig. 5 of the drawing. It will also appear that the crossing of the wire, as at 40, in forming the loop 37 forms a substantially closed opening 39 in the loop.

Before proceeding to describe the structure in Figs. 7, 8 and 9, attention is directed to Fig. 10, which is shown to illustrate the manner of assembling clips which can be united, as shown in Fig. 6, and also as illustrated in Fig. 9. However, in Fig. 10, the clips 15 are shown. These clips are united by threading the loops 21 over the shanks of the large and small loops 16 and 17 in order to first dispose the loops 21 within the smaller loops 17. Thereafter, these loops may be brought together in the assembled relationship shown in Fig. 6 by springing the loop 21 of one clip across the neck portion 22 of the adjacent clip, particularly when these neck portions are contracted to form substantially closed openings as at 23.

In Figs. 7 to 9 inclusive is shown at 41 another form of clip which differs from the clip 15 simply in providing what may be termed open mounting loops 42 rather than closed mounting loops, as at 21 and 37. The loops 42 are twisted, however, at 50 what might be termed neck portions 43, so as to dispose the loops 42 at right angles to the loops of the clip, the same as the loops 21. This type of more or less open loop is desirable for use on mounting or binder rods, such as the rod 44, shown in Fig. 8 and the rod 45, shown in Fig. 9. This rod might constitute the mounting of a binder or in itself comprise a binder to which a number of sheets or groups of sheets may be attached.

In Fig. 8 of the drawing the clips 41 are mounted individually on the rod 44 so that they may be freely moved circumferentially as well as longitudinally on this rod for positioning the clips in any desired position thereon, with sheets or other devices coupled therewith maintained in any position with respect to the rod.

In Fig. 9 of the drawing is shown another use of the clips 41 which differs from the use illustrated in Fig. 8, simply in uniting adjacent devices 41 one with the other by intercoupling the loops 42 in the same manner as taught in Figs. 6 and 10 of the drawing and by making the loops 42 sufficiently large to receive the rod 45 which will be free to pass through the intercoupled loops. With the structure shown in Fig. 9 of the draw-

ing, the separate clip devices will have a circumferential movement one with respect to the other within limits of adjacent devices or clips, but will be retained in a unit relationship against relative displacement along the supporting rod. This type of construction will keep the sheets or other articles or members against relative movement one with respect to the other along the supporting rod.

It will be understood that devices of the kind under consideration may be sold and distributed as individual devices and adapted for various uses or assemblages, some of which have been illustrated in the accompanying drawing. On the other hand, factory assembled units may be manufactured and sold to adapt the units to specific uses. For example, in the teachings shown in Fig. 2 of the drawing, units may be made up of two or more clips on a common mounting 25, the mounting being made of a size to suit the number of clips thereon. The same will also be true of the structure shown in Fig. 3, where the ring may be made large enough to take the number of clips desired in the unit and this will also be true of the structure shown in Figs. 4 and 6 of the drawing as well as the unit assemblages that would be adapted for the use indicated in Fig. 9.

In satisfying requirements in various office or business establishments, the respective units may be all the same in a single package, which may comprise many of the units equivalent, for example, to the sale of a hundred clips to the package, or this same package may have a varied combination of units to adapt the same to different required uses.

In producing clips of the kind under consideration, the mounting or supporting end portions thereof which comprises the loops 21, 37 and 42, also form finger pieces facilitating the attachment of papers or other articles to the clips. These loops will not add to the amount of material employed in the resulting clip device to any great degree, and the added costs essential to the formation of these loops is comparatively slight, thus the resulting added cost of the device to the consumer is minimized.

In some instances, the clips of units such as illustrated in Figs. 2 and 3 for example, as well as in other figures, may have distinct colors so as to distinguish the sheets or articles coupled therewith one from the other. This would be extremely simple if the clip devices were formed from plastic materials where different colors were used in the plastics. Where metal clips are used, the same result can be accomplished by plating operations performed on the material employed.

Having fully described my invention, what I claim as new and desire to secure by Letters Patent is:

- 5 1. A clip of the class described, comprising a pair of sheet engaging loops normally disposed one within the other in substantially the same plane, said loops being integrally joined at one end thereof by a third loop disposed in a plane substantially at right angles to and beyond both surfaces of the plane of said first named loops and yieldably supporting said first named loops in said plane, and said last named loop forming a separate article engaging means on said clip.
- 10 2. A clip of the class described, comprising a pair of sheet engaging loops normally disposed one within the other in substantially the same plane, said loops being integrally joined at one end thereof by a third loop disposed in a plane substantially at right angles to and beyond both surfaces of the plane of said first named loops and yieldably supporting said first named loops in said plane, and said last named loop joining said first named loops in a restricted neck portion and forming a separate article engaging means on said clip.
- 15 3. A clip device of the class described comprising a plurality of clips, each clip comprising a pair of elongated loops normally disposed one within the other in substantially the same plane, said loops being integrally joined at one end thereof by a third loop disposed in a plane substantially at right angles to the plane of said first named loops and yieldably supporting said first named loops in said plane, and said third loops of adjacent clips being interengaged in maintaining the clips in assemblage.

HUGH P. BOTTs.
